UNITED STATES PATENT OFFICE.

OTTO L. HEMMING, OF NEW HAVEN, CONNECTICUT.

PROCESS OF MAKING FOLDING ARTICLES.

1,280,462.

Specification of Letters Patent. Patented Oct. 1, 1918.

Application filed November 8, 1917. Serial No. 200,921.

To all whom it may concern:

Be it known that I, OTTO L. HEMMING, a citizen of the United States, residing at New Haven, in the county of New Haven 5 and State of Connecticut, have invented a certain Process of Making Folding Articles, of which the following is a specification, reference being had therein to the accompanying drawings.

10 My invention has relation to the manufacture of folding articles, such as knives, button hooks, cork screws, and the like.

The object of my invention, among other things, is to provide a durable and efficient 15 article that is composed of a minimum number of parts and produced by my improved process of manufacture, which consists firstly in making the handle portion of the article of one piece of sheet metal, secondly, 20 inserting a fixed anchoring post within the handle for a spring which controls the opening and closing movements of the folding member of the article, and thirdly, finishing said handle portion, all of which mentioned 25 operations are effected previously to the complete assembling of all of the parts.

The invention will be hereinafter described with reference to the accompanying drawings, wherein,

30 Fig. 1 is a composite view showing the principal elements of a folding knife disassembled, the blank for the handle being illustrated as it appears after the blanking operation.

35 Fig. 2 is a view of the handle blank after the first operation thereon;

Fig. 3 is a sectional view thereof taken upon line 3—3 of Fig. 2;

40 Fig. 4 is a view of the handle blank after the second operation thereon;

Fig. 5 is a sectional view thereof taken upon line 5—5 of Fig. 4;

Fig. 6 is a view showing the handle completed;

45 Fig. 7 is an edgewise view of the front of the handle as shown in its completed form in Fig. 6; and

Figs. 8 and 9 are respectively cross sectional and longitudinal sectional views 50 showing the assembled knife, the sections being taken respectively upon lines 8—8 and 9—9 of Figs. 9 and 8.

In carrying out the embodiment of the invention as illustrated in said drawings, 55 the process is employed in constructing a novel form of knife handle, which together

with the construction and arrangement of the blade and the spring for maintaining the same in open and closed positions forms the subject matter of another application.

The handle of the knife, designated by the numeral 1, is composed of a single piece of sheet metal shaped and bent to form a pocket 2 for the knife blade when the latter is in a closed position. Convexed or outwardly swelling sides 3 offer a convenient grip for the user, and the end 4 is flattened to receive and hold the shank 5 of the blade 6 against lateral or side play. Spring 7 employed for controlling the opening and closing movement of the blade, engages the shoulder 8 of the blade when open, and the square end 9 is engaged by said spring when the blade is in intermediate and closed positions. The blade 6 is pivotally mounted 75 upon a rivet 10, and the spring 7 is held in place by engagement of the shouldered or hooked end 12 with the rivet or post 13 located between the ends of the handle substantially as shown.

80 From the foregoing description of the parts of the knife, it will be noted that the complete knife is composed of three parts or pieces only, namely the handle 1, spring 7 and blade 5, and in assembling such parts 85 only the two rivets 10 and 13 are required.

In the process of making the handle, a blank 14, having a configuration substantially as shown in Fig. 1, is cut from a flat piece of metal, and at the cutting operation 90 may be slightly bulged or swelled, as shown at 15.

The second operation consists in increasing the depth of the bulge or swelling 15, punching holes 16 and 17 respectively for 95 the rivets 10 and 13, which are used in assembling the parts of the knife. In this operation the notched and rounded end 18 of the blank is turned over to form the end lips 19.

100 In the next operation the blank is folded so as to bring the two sides together, as shown in Figs. 4, 5 and 6. The rivet 13 is next inserted and fastened in place by upsetting the ends thereof, after which the handle is finished by plating, japanning, polishing or by other means.

The above operations conclude the process of making the handle, which, it will be noted, is completely finished, before the assembling therewith of the other parts.

110 In assembling, the first step is to insert

the spring 7 in place within the pocket 2 so that the shouldered or hooked end 12 engages rivet 13 and then the blade and rivet 10 are inserted, the latter rivet being preferably upset by spinning so as not to mar the finish of the handle.

Having described my invention, what I claim as new and desire to secure by Letters Patent, is,—

- 10 1. In the manufacture of articles of the class described, a method of making the handle portion of the article of a one piece sheet metal blank and consisting in forming substantially parallel depressions longitudinally in the blank leaving a portion of the blank at one end flat, perforating said blank in each depression substantially at a central point and at each side of the flat portion of the blank and subsequently bending said blank along the longitudinal center thereof so as to provide an open pocket
- 15 20

between said flat end portion and said depressions.

2. In the manufacture of articles of the class described, a method of making the handle portion of the article and providing means for anchoring a controlling spring therein, consisting in making the handle portion of a one piece sheet metal blank having depressions formed longitudinally therein leaving a portion of the blank at one end flat, a perforation formed in each depression substantially at a central point, bending said blank along the longitudinal center thereof so as to provide an open pocket between said flat end portion and the depressions, and subsequently securing a controlling spring anchoring post in said perforations within the handle portion.

In testimony whereof I have hereunto affixed my signature.

OTTO L. HEMMING.
